UNITED STATES PATENT OFFICE.

PAUL H. SCHULZ AND CHRISTIAN JESSEN, OF MILWAUKEE, WISCONSIN.

DESIGN FOR A TRAFFIC SIGNAL-HEAD.

Application filed May 16, 1922. Serial No. 2,271. Term of patent 14 years.

To all whom it may concern:

Be it known that we, PAUL H. SCHULZ and CHRISTIAN JESSEN, both citizens of the United States, residing at Milwaukee, in the county of Milwaukee, and State of Wisconsin, have invented a new, original, and ornamental Design for Traffic Signal-Head, of which the following is a specification, reference being had to the accompanying drawing, forming part thereof.

Figure 1 is a plan view of the traffic signal-head constituting my design.

Figure 2 is an elevational view of same, and

Figure 3 is an elevational view of same.

We claim:—

The ornamental design for a traffic signal-head, as shown.

In testimony that we claim the foregoing we have hereunto set our hands at Milwaukee, in the county of Milwaukee and State of Wisconsin.

PAUL H. SCHULZ.
CHRISTIAN JESSEN.
